(57) **CLAIM**

The ornamental design for a chair, as shown and described.

DESCRIPTION

FIG. 1 is a perspective view of the chair showing my design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a cross-sectional view that is taken along a line
VIII-VIII of FIG. 6; and,
FIG. 9 is a reference view thereof showing only the part
represented by solid lines in the perspective view of FIG. 1.
The broken lines in all FIGs are for the purpose of illustrating
the environment in which the design is associated and
form no part of the claimed design.
